(57) **CLAIM**

The ornamental design for a notched edge carpenter square design, substantially as shown and described.

DESCRIPTION

FIG. 1 is a perspective view of the carpenter square design of the present invention;

FIG. 2 is a front plan view of the notched edge carpenter square design;

FIG. 3 is a side plan view of the notched edge of the notched edge carpenter square design;

FIG. 4 is a side plan view of the perpendicular edge that extends perpendicular from the notched edge;

FIG. 5 is a side plan view of the angled edge that extends between the notched edge and the perpendicular edge;

FIG. 6 is a top plan view of the carpenter square showing the angled edge;

FIG. 7 is a plan view of the back side of the notched edge carpenter square design; and,

FIG. 8 is an exploded view of the notched edge of the carpenter square design of the oval section indicated in FIG. 2.
